Application May 14, 1949, Serial No. 93,346

9 Claims. (Cl. 112—258)

1

This invention relates to sewing units of the type including a sewing machine, an individual drive therefor and a readily shiftable supporting structure. More particularly it relates to a unit of this character in which the sewing machine and its drive are mounted upon a pedestal or column extending upwardly from a large floor engaging base which provides a steady and sturdy support but is free to be shifted about to facilitate rearrangement of a series of machines forming a sewing line.

A primary object of the invention has been to provide a mounting for the machine which enables easy adjustment of the machine on its support in a variety of different ways and directions to accommodate the unit to different operators and for the performance of different operations, to best advantage.

An important specific object has been to provide a pedestal type of support which will permit tilting of the sewing machine to any desired extent toward or away from the operator in order to present the work supporting surface at the most advantageous angle for a particular operation and one most convenient for a particular operator.

Another object has been to provide a support of the character indicated which will permit simple and easy adjustment of the machine in both a vertical and a horizontal direction so as to position the machine most advantageously in relation to the supporting column for any selected operator and operation.

A further object has been to provide a sewing unit having the foregoing capabilities with simple and effective control means, adapted for convenient operation by the operator, for throwing the machine into and out of operation and for lifting the presser foot, and the like.

The foregoing objects have been attained in relation to sewing machines of different types, such as a feed-off-the-arm machine and a flatbed machine. Certain special features have been devised in relation to each of these types of machines and it will be understood that the invention may be readily adapted for machines of other types.

An outstanding advantage of the invention is that it enables the production of certain standard units which may readily be adapted, as indicated above, for most convenient use by different operators of different stature and personal preferences, and for use in performing different operations. In certain operations it is important to look down upon the work in a direction substan-

2

tially normal to the work support and in such operations it is desirable to tilt the machine forwardly toward the operator so that the work support is inclined upwardly at a suitable angle away from the operator. In other operations it is important to observe more closely the manner in which the work approaches the stitching point and is fed under and past the presser foot. For such operations it is desirable to tilt the machine rearwardly away from the operator to incline the work supports downwardly at an appropriate angle away from the operator. Different operators moreover, according to the preferences, find it desirable to assume different angular positions in relation to the work support for a particular operation and because of their varying heights and other characteristics find it desirable to vary the height of the machine and its position horizontally in relation to the treadles and supporting column. The present invention provides the necessary adjustment for all of these purposes.

Other objects, features and advantages of the invention will appear from the detailed description of certain illustrative forms of the same which will now be given in conjunction with the accompanying drawings, in which:

Fig. 1 is an elevational view showing one form of sewing unit embodying the invention, parts being broken away to condense the view and to show normally concealed parts;

Fig. 2 is a detail view on an enlarged scale showing the collar provided at the upper end of the pedestal column;

Fig. 3 is a plan view of the sewing unit with parts broken away to disclose more clearly certain concealed parts of the structure;

Fig. 4 is a detail view in plan showing a support member embodied in the unit of Fig. 1;

Fig. 5 is a plan view of the collar shown in Fig. 2;

Fig. 6 is a view, partly in plan and partly in horizontal section, taken substantially along the line 6—6 of Fig. 1;

Fig. 7 is a front elevational view of a modified form of sewing unit embodying a flat bed sewing machine, a portion of the power drive being broken away;

Fig. 8 is an end elevational view of the unit of Fig. 7, taken from the right in Fig. 7;

Fig. 9 is a plan view of the unit of Fig. 7; and

Fig. 10 is an end elevational view of the upper portion of the unit of Fig. 7 showing the sewing machine and its drive in a tilted position.

Referring now to Figs. 1 to 6 of the drawings, there is illustrated, as one embodiment of the

invention, a unit having a feed-off-the-arm type of sewing machine similar to that disclosed in the Christensen, et al. Patent No. 1,741,095, granted December 24, 1929. It is also illustrated, in modified form, in Christensen Patent No. 2,374,731, granted May 1, 1945, and in the Sauer application, Serial No. 602,198 filed June 29, 1945. The unit as a whole is similar in many respects to that disclosed in the Christensen, et al. application Serial No. 704,822, filed October 22, 1946. Many features and adjuncts disclosed in the last mentioned application may be incorporated in the new construction, though they are not herein specifically shown and described.

The improved sewing unit comprises a pedestal support having a floor engaging member 10 provided with downwardly extending bosses 11 forming feet adapted to engage the floor and retain the unit in any set position simply by frictional coaction with the floor. Adjacent one end of the member 10 there is provided a vertically extending split collar 12 adapted to receive the lower end of a tubular column 13. The latter is held by a series of clamping screws 14 adapted to squeeze the split collar together around the column. The total height of the pedestal may be varied somewhat by adjusting the extent to which the column is inserted in the collar 12. Adjacent its upper end the column 13 carries a split collar 15 having, in plan, the configuration illustrated in Fig. 5. Clamping screws 16 serve to tighten the collar upon the upper end of the column to hold it in place. The collar may be adjusted both axially and angularly in relation to the column to vary the height of the sewing machine above the floor and to vary its angular relation to the floor engaging member 10. A separate split collar 17, secured to the column by a screw 18, may be provided beneath the collar 15 to assist in maintaining its vertical position on the column.

As best shown in Figs. 2 and 5, the collar 15 is provided with a relatively broad, flat face 19 from which projects a trunnion or stud 20. The latter is adapted to carry, pivotally, a main support member designated generally by reference character 21. Member 21 has a downwardly extending vertical flange portion 22 carrying a hub-like extension 23 adapted to fit snugly over the trunnion 20. The inner face of the flange 22 is flat and arranged to lie against the surface 19 of the collar. Arcuate slots 24, extending through the flange 22, are disposed at opposite sides of the hub 23 and are curved about the axis of the latter. These slots are adapted to receive the shanks of a pair of bolts 25 which have screw threaded engagement with openings 26 in the collar 15. The latter is also provided with a series of holes 27 arranged in an arc about the center of the trunnion 20 in a region below the latter. A large headed pin 28, carried by the flange 22 and passing through a suitable opening in the latter, is adapted to cooperate with one or another of the holes 27. Pin 28 is urged inwardly by a flat spring element 29, which is secured to the flange 22 and forked to straddle a reduced portion of the pin. It will be apparent from the foregoing that when it is desired to change the angular relation between the support member 21 and the collar 15, it is simply necessary to loosen the screws 25 and to withdraw the pin 28 from the engaged hole 27. The member 21, with all of the parts carried thereby, to be explained hereinafter, may then be tilted either forwardly or backwardly to a new position and the pin

28 may then be permitted to enter a new hole 27. Screws 25 may then be retightened to complete the adjustment.

Support member 21 has a horizontally disposed portion 30 on which is mounted a power driving unit 31. This is preferably an electric motor and clutch unit of the type commonly designated an electric transmitter. It may suitably be of the same construction as that disclosed in the above mentioned Christensen, et al. application. Bolts 32 extending downwardly from the power unit are adapted to cooperate with elongated slots 33 in the portion 30 of the support member and may serve to clamp the power unit to the latter. Provision of the elongated slots 33 makes it possible to adjust the position of the power unit laterally on the support member, at right angles to the axis of the unit, for belt tightening purposes, as will presently appear.

An extension 37 of the support member 21 is provided with a flat surface 38 against which may be placed a corresponding surface on the frame 39 of the sewing machine 40 of the feed-off-the-arm type indicated above. Suitable bolts or screws may be employed for attaching the sewing machine frame to the extension 37. It will be understood that the sewing machine embodies all of the usual mechanisms for stitch formation, feeding of the work, control of the thread, and the like. It is provided with a work arm 41 which is normally disposed horizontally, that is when the support member 21 is in its normal or central position. By tilting the member 21 forwardly toward the operator or backwardly away from the operator, the arm 41 may be inclined either upwardly or downwardly from the horizontal, as desired. A combined hand wheel and pulley 42 is provided to supply power to the sewing machine for driving the latter, this pulley being connected by a belt 43 with the pulley 36 of the power unit.

A bracket 44 having a split collar or hub adapted to surround and grip a sleeve forming part of the clutch of the power unit, in a manner well known in the art and as is more fully disclosed in the abovementioned Christensen, et al. application, has a laterally extending arm 45 which is connected by a bolt 46 with the upper end of a rod 47. The latter is connected by a coupling 48 with another vertically extending rod 49. Rods 47 and 49 are in effect a single rod which may be lengthened or shortened by varying the extent to which they overlap at the coupling 48. This rod extends downwardly through the column to its lower end and there is swivelly connected by a bolt 50 with the end of a curved arm 51. This, at its opposite end, carries or is secured to a hub 52 keyed to a rock shaft 53 mounted in bearings 54, 55, and 56 in the member 10. A treadle 57, Fig. 1, is secured to the rock shaft 53 by means of downwardly extending arms 58 and 59 of the treadle which are keyed to the shaft. It will be seen that, through the foregoing connections, rocking of the treadle in a clockwise direction, as viewed from the right in Fig. 6, will draw the rod 49 downwardly and correspondingly rock the bracket 44 and the connected sleeve, thereby causing the engagement of the clutch in a well known manner. At the same time another laterally extending arm 61 of the bracket 44 may serve to operate a lubricant pump through a connection 62 with an arm 63 associated with the pump. The latter is not herein disclosed, but for further details regarding it, reference may

be had to the abovementioned Christensen, et al. application.

Another treadle 64 carries a rod or shaft 65 which is journalled in bearings 66 mounted in the base member 10. At its rearward end the treadle 64 carries a diagonally disposed rod 67 which extends beneath the lower end of the column 13 and is there connected by a bolt 68 with a rod 69 that extends upwardly through the column. At its upper end the rod 69 has an enlarged head 70 (Fig. 1), which has a ball joint construction by a bolt 71 (Fig. 3), with an arm 72 secured to a rock shaft 73. The latter is journalled at its opposite ends in bearings 74 and 75 carried by the support member 21. An arm 76 secured to the shaft 73 adjacent the bearing 75 is connected by a link 76a with an arm 77 which is, in turn, connected by a link 77a with an arm 78. This, as disclosed in the above mentioned patents and pending applications, is arranged to lift the presser bar of the sewing machine. The upper end of the presser bar, indicated at 79 in Fig. 3, is engaged by a spring 80 which normally urges the bar downwardly to engage its presser foot with the work. Rocking of the treadle 64 serves to lift the presser bar and presser foot through the connections described. It will be understood that springs are suitably provided for urging the parts operated by the treadles 57 and 64 into a normal inactive position. These springs are not disclosed herein, but are shown in said Christensen, et al. application.

Any or all of the features and adjuncts disclosed in the above mentioned patents and pending applications, such as the thread controlling means and the like, may be incorporated in the present construction. By the provision of the pivotal supporting member 21, it is possible to tilt the sewing machine either into the position illustrated in Fig. 1 or in the opposite direction, as best suited for the particular operator and the operation involved. At the same time provision is made for various other adjustments. Thus by lifting or turning the collar 15 in relation to the column 13 the position of the work arm 41 may be suitably varied in relation to the treadles, both as to height and horizontal angular position. Tightening of the belt 43 may be effected by adjusting the power unit laterally on the member 21. All of the various adjustments described are permitted by the operating connections involved. The forward or rearward tilting of the support member 21 may be accomplished without altering the connections from the treadles but provision may be made for varying the length of these connections whenever desired, as when the collar 15 is raised or lowered. Suitable means for this purpose will be described in relation to corresponding connections provided for the second embodiment of the invention to be presently described.

Referring now to Figs. 7 to 10 inclusive, there is shown another embodiment of the invention in which a flat bed sewing machine is mounted upon a pedestal support with the capability of tilting the machine either forwardly or backwardly to suit a particular operator and a particular operation to be performed. As in the first embodiment, the pedestal comprises a floor engaging member 85 having footlike projections 86 adapted to frictionally engage the floor. Rising vertically from the member 85, toward one end of the latter, is a split hub or sleeve 87 adapted to receive a hollow column 88. The latter is clamped in the hub by means of screws 89. 75

As in the first form, the height of the column may be varied to some extent by varying the distance to which the column 88 is inserted in the hub 87. Adjacent its upper end the column 88 is provided with a collar 90 which has its lower portion split vertically and provided with clamping screws 91 to attach the same firmly to the column. Further vertical adjustment of the overall height of the support is provided by varying the vertical location of the collar 90 in relation to the column. A separate collar 92 of split construction, clamped to the column 88 by means of a screw 93, may be provided just below the collar 90 to assist in supporting the load. It also permits loosening of the collar 90 for angular adjustment on the latter without altering its vertical position. Projecting laterally from the collar 90 at diametrically opposite sides are trunnions 94 and 95. The trunnion 95 may suitably be in a region directly above the split in the collar. A tiltable support member 96 is mounted on the trunnions by suitable bearing or clamping means. For this purpose a projection 97, which extends downwardly from the member 96, is provided with a bearing surface adapted to cooperate with the trunnion 94. A lower cap 98 completes the bearing, this cap being secured to the projection by screws 99. The arrangement is preferably such that the two sections of the bearing may be clamped tightly about the trunnion to assist in holding the support in any position to which it may be adjusted. Similarly, a downward extension 100 of the support member 96 has a bearing engagement with the trunnion 95 and this bearing is completed by a lower cap 101 secured by means of screws 102. These parts may likewise assist in retaining the support in any adjusted position by tightly clamping the trunnion 95. 40

Trunnion 95 is provided with worm wheel teeth 103 around a portion of its circumference. If desired, these teeth may be provided completely around the trunnion. Cooperating with the teeth 103 is a worm portion 104 on a rotatable stud 105. The latter has an enlarged, knurled head 106 at one end by which it may be readily rotated. At its opposite end the stud has fixed thereon a collar 107 which serves to hold it in place. Upon loosening the screws 99 and 102, to unclamp the support from the trunnions, and then rotating the knurled head 106, the support member 96 may be caused to revolve bodily around the supporting trunnions in one direction or the other depending upon the direction of rotation of the stud 105. It may be tilted rearwardly, for example, into the position indicated in Figure 10, or it may be tilted forwardly of its central, horizontal position. When the support member has been tilted to the desired position, it is held by the coaction of the worm and worm wheel teeth, but it is preferably clamped more firmly by tightening the screws 99 and 102. 45

To the upper surface of the support member 96 is secured a table board 108, this being attached in any suitable way, as by means of bolts 109. Table board 108 is provided with a large opening 110 adapted to receive a downwardly extending portion 111 of the frame of a flat bed sewing machine 112 which may, for example, be of the lockstitch type. Support member 96 is also formed to provide an opening for the downward extension 111 of the sewing machine frame. For this purpose the support member, as best shown in Fig. 9, is forked to provide extensions 50 55 60 65 70 75

113 and 114 parallel with the front and back surfaces of the portion 111 of the sewing machine. The sewing machine is preferably supported directly by the member 96 at the four points designated 115 in Fig. 9. To eliminate noise and deaden vibration, sections of felt or similar material are preferably placed between the bottom of the sewing machine and the surfaces of the member 96 on which the machine rests.

The base of the sewing machine is preferably hingedly supported by the table top 108 and for this purpose hinges 116 and 117 of conventional form, may be provided. This enables tilting of the sewing machine backwardly to expose the bottom of the machine for servicing and inspection. A pin 118 extending upwardly from the table top is adapted to engage the frame of the machine as it is in its rearwardly tilted position and support the same in such position. It will be understood that the sewing machine may be of any desired construction and may, for example, be of the type disclosed in Patent No. 2,446,245, granted to Charles F. Rubel on August 3, 1948. It has an overhanging arm 119 which carries a needle head at its outer end for supporting a reciprocating needle bar, a presser bar, and the like; a rotary hook, work feeding devices and the like are provided in the base 111. Further description of the details of the sewing machine is believed to be unnecessary. It may suitably be driven through a combined hand-wheel and pulley 120 mounted on a shaft which extends longitudinally of the arm 119 and projects beyond the frame of the machine. This pulley is connected by a belt 121 with a pulley 122 on a power drive unit indicated generally at 123.

The power drive may be of the same type as described in connection with Fig. 1, consisting of an electric motor and a clutch. It is suspended from an extension 124 of the support member 96. This extension is provided with a plurality of elongated slots 125, 126, and 127 adapted to receive bolts 128, which may be either solid or hollow, extending upwardly from the power unit when positioned as shown. Noise and vibration isolating pads or elements 129 are preferably employed between the various metallic surfaces, as best shown in Fig. 8. These pads may be in the form of felt or rubber washers or the like, surrounding the bolts 128. They may also, if desired, be provided with sleeves or collars of reduced diameter to cooperate with the openings in the support member and the frame of the power unit to hold the bolts spaced from the walls of these openings. The clutch of the power unit may be of the type having a rockable and axially shiftable sleeve providing a bearing for the driven shaft which carries the pulley 122. This sleeve, as is well known in the art, is adapted to be rocked in order to bring about engagement of the clutch. An arm 130 secured to the sleeve adjacent one end is provided with an eyelet member 131 secured to the arm by a set screw 132. A rod 133 extending through the eyelet is held in a centralized position by a pair of springs 134 and 135. Spring 134, preferably of conical form, cooperates at its smaller end with a head 136 provided at the upper end of the rod. At its other end the spring engages a washer 137 and forces this against the upper surface of the eyelet 131. Spring 135 which is of similar form urges a washer 138 against the undersurface of the eyelet and cooperates at its opposite end with a collar 139 secured to the rod 133. In

order to permit lengthening or shortening of the rod in accordance with adjustment of the collar 90, it is formed in two sections, the lower section being designated 140. The two sections may be 5 clamped together in any desired position by means of a clamping collar 140a. At its lower end the rod 140 is connected, preferably by a ball joint, with the outer end of an arm 141 secured to a rock shaft 142 (Figs. 7 and 8). This rock 10 shaft is mounted in suitable bearings carried by the portion 85 of the pedestal and has secured to it, at a convenient point, a foot treadle 143. Through the connections described the power 15 drive may be thrown into and out of operation by rocking of the treadle 143.

Another treadle 144, pivotally mounted at its forward end by a shaft 145 in suitable bearings carried by the base portion 85 of the pedestal, has a laterally extending stud 146 adjacent its 20 opposite end. This stud is connected by a rod 147 with a second rod 148 through a coupling or clamping collar 149. Rod 147 has a swivelled or ball connection with the stud 146. The upper 25 end of rod 148 is connected indirectly, through a rock lever (not shown), carried by the sewing machine frame, with another rod 148a which as best shown in Figs. 8 and 10, is connected with an arm 150 extending rearwardly from the sewing machine frame. This arm, as will be understood, is connected with suitable means for lifting the presser bar of the sewing machine. The means for this purpose may be of the type disclosed in the patent to Quist No. 2,414,168, granted on January 14, 1947. However, the rock lever mentioned will so connect the rods 148 and 148a as to cause these to move in the same direction. Provision of this rock lever enables 30 tilting of the sewing machine on its hinges, as explained, without disconnecting the rods 147, 148 and 148a. If desired, however, the rod 148 may be connected directly with arm 150 and provision made for disconnecting the rod from the arm when the machine is to be tilted rearwardly on its hinges, or the rods 148 and 148a may 35 simply be connected by a suitable swivel joint for the purpose.

As in the first embodiment, the support 96 and the various parts carried by it may be readily adjusted in a variety of different ways to suit a particular operator and type of operation. It 40 may be elevated or lowered; it may be shifted angularly about the axis of the column 88, if desired, and it may be tilted to any desired angle from the horizontal, either forwardly or rearwardly. The power unit may be shifted laterally of the support for belt tightening purposes.

While several embodiments of the invention have been disclosed in considerable detail, it will be understood that it may be embodied in a variety of other forms. Certain features disclosed 45 in connection with one embodiment may, if desired, be incorporated in the other. Various other changes may be made without departing from the general principles and scope of the invention.

60 What we claim is:

1. A sewing unit comprising a supporting structure having a floor engaging portion and a vertically extending column carried thereby at one 65 side of the center thereof, a collar mounted on said column adjacent its upper end, a substantially flat support carried by said collar in a substantially horizontal position, horizontal pivot means securing said support to said collar, said means enabling angular adjustment of said support

about a horizontal axis on said collar, means serving to retain said support in set position on said collar, a sewing machine secured to said support for adjustment therewith, said sewing machine having a work supporting surface shiftable upon such adjustment to opposite sides of a horizontally disposed position, a power unit also secured to said support for adjustment therewith, and means connecting said power unit with said machine for driving the latter.

2. A sewing unit comprising a supporting structure having a floor engaging portion and a vertically extending column carried thereby at one side of the center thereof, a collar mounted on said column adjacent its upper end, a substantially flat support carried by said collar in a substantially horizontal position, horizontal pivot means securing said support to said collar, said means enabling angular adjustment of said support about a horizontal axis on said collar for upward and downward inclination to the horizontal, means serving to retain said support in set position on said collar, a sewing machine secured to said support for adjustment therewith, said machine having a work supporting member substantially parallel with said support, a power unit also secured to said support for adjustment therewith, means connecting said power unit with said machine for driving the latter, a treadle carried by said floor engaging portion of said supporting structure, and connections from said treadle for controlling the operation of said machine by said power unit.

3. A sewing unit comprising a supporting structure having a floor engaging portion and a column rising therefrom, a normally horizontal support member mounted on said column adjacent its upper end, said column and member being provided with cooperating means enabling tilting of said member in either direction from the horizontal about a horizontal axis, means for locking said member in the position to which it is adjusted, and a sewing machine secured to said member, said sewing machine having a work supporting surface substantially parallel with said support member and arranged to be inclined upwardly or downwardly in a direction away from the position assumed by the operator thereof upon the angular adjustment of said member.

4. A sewing unit comprising a supporting structure having a floor engaging portion and a column rising therefrom, a normally horizontal support member mounted on said column adjacent its upper end, said column and member being provided with cooperating means enabling tilting of said member in either direction from the horizontal about a horizontal axis, said means also enabling bodily movement of said member along said axis, means for locking said member in the position to which it is adjusted, and a sewing machine secured to said member, said sewing machine having a work supporting surface substantially parallel with said support member and arranged to be inclined upwardly or downwardly in a direction away from the position assumed by the operator thereof upon the angular adjustment of said member.

5. A sewing unit comprising a supporting structure having a floor engaging portion and a column rising therefrom, a normally horizontal support member mounted on said column adjacent its upper end, said column and member being provided with cooperating means enabling tilting of said member in either direction from the horizontal about a horizontal axis, means for locking said

member in the position to which it is adjusted, a sewing machine secured to said member, said sewing machine having a work supporting surface substantially parallel with said support member and arranged to be inclined upwardly or downwardly in a direction away from the position assumed by the operator thereof upon the angular adjustment of said member, a driving unit also secured to said member, and means for connecting said driving unit with said sewing machine.

6. A sewing unit comprising a supporting structure having a floor engaging portion and a column rising therefrom, a normally horizontal support member mounted on said column adjacent its upper end, said column and member being provided with cooperating means enabling tilting of said member in either direction from the horizontal about a horizontal axis, means for locking said member in the position to which it is adjusted, a sewing machine secured to said member, said sewing machine having a work supporting surface substantially parallel with said support member and arranged to be inclined upwardly or downwardly in a direction away from the position assumed by the operator thereof upon the angular adjustment of said member, a driving unit also secured to said member, said driving unit comprising a motor and a clutch having driving and driven elements, means connecting the driven element of the clutch with said sewing machine, an arm connected with said clutch for controlling the engagement and disengagement thereof, said arm extending to a point over the upper end of said column, a treadle carried by said floor engaging portion, and connections from said treadle to said arm including a rod extending upwardly through said column.

7. A sewing unit comprising a supporting structure having a floor engaging portion and a column rising therefrom, a normally horizontal support member mounted on said column adjacent its upper end, said column and member being provided with cooperating means enabling tilting of said member in either direction from the horizontal about a horizontal axis, means for locking said member in the position to which it is adjusted, a sewing machine secured to said member, said sewing machine having a work supporting surface substantially parallel with said support member and arranged to be inclined upwardly or downwardly in a direction away from the position assumed by the operator thereof upon the angular adjustment of said member, a driving unit, a belt connecting said unit with said sewing machine and means for securing said driving unit to said member, said securing means enabling lateral adjustment of said driving unit on said member for belt tightening purposes.

8. A sewing unit comprising a supporting structure having a floor engaging portion and a vertically extending column carried thereby at one side of the center thereof, a collar mounted on said column adjacent its upper end, a substantially flat support carried by said collar in a substantially horizontal position, horizontal pivot means securing said support to said collar, and means enabling angular adjustment of said support about a horizontal axis on said collar, means serving to retain said support in set position on said collar, a sewing machine secured to said support for adjustment therewith, said sewing machine being of the feed-off-the-arm type and having a work arm with its axis disposed substantially perpendicular to the vertical plane containing said horizontal axis when said support is in its

11

central position, a power unit also secured to said support for adjustment therewith, and means connecting said power unit with said machine for driving the latter.

9. A sewing unit comprising a supporting structure having a floor engaging portion and a vertically extending column carried thereby at one side of the center thereof, a collar mounted on said column adjacent its upper end, said collar having a trunnion projecting horizontally therefrom, a support having a portion which is normally disposed horizontally and a part having a bearing engagement with said trunnion for tilting of said support in opposite directions from the horizontal, means for locking said support in a plurality of angular positions in relation to said

5 trunnion, a sewing machine and a power drive unit secured to said support, said sewing machine having a work supporting surface substantially parallel with said support, and means for connecting said power drive unit with said sewing machine for driving the latter.

GEORGE SAUER.
